UNITED STATES PATENT OFFICE.

CLAUDE M. GARLAND, OF CHICAGO, ILLINOIS.

APPARATUS FOR DEVOLATILIZING COAL, SHALE, ETC.

Application filed January 28, 1920 Serial No. 354,531.

To all whom it may concern:

Be it known that I, CLAUDE M. GARLAND, a citizen of the United States, residing in Chicago, in the county of Cook and State 5 of Illinois, have invented new and useful Improvements in Apparatus for Devolatilizing Coals, Shales, Etc., of which the following is a specification.

My invention has for its object the 10 vision of improved means for coking bituminous coal and devolatilizing such fuels as wood, lignite, shale, etc., whereby the time required for devolatilizing is greatly reduced, the by-products resulting therefrom increased in quantity and the labor required in the operation greatly lessened.

Further objects and advantages of my invention will be set forth in the description that follows.

20 The apparatus is intended for the coking of fuels by the low temperature process. In the low temperature process of coking it has been found that in order to coke rapidly and to produce a uniform product 25 the fuel must be divided into thin layers. Otherwise the heat does not reach the center of the mass. This action has been fully described in my Patent 1,391,825 granted September 27, 1921. In the low temperature 30 process the temperatures used in heating the fuel do not exceed 1200 degrees F. and may be as low as 750 degrees.

In my apparatus the coking or devolatilizing is carried out preferably in narrow 35 vertical cast iron retorts of any convenient length and breadth but of only a few inches in thickness, for example a practical size would be 12 feet in length by 18 inches in breadth by 4 inches in thickness.

40 These retorts are placed in a heating chamber and arranged in parallel rows. The retorts in each row being separated by a gas space of about one inch. This permits the heat to pass into the fuel contained 45 in the retorts on four sides and greatly lessens the coking time.

The heat for coking is supplied through 50 pipes in the bottom of the heating chamber which extend between the rows of retorts. Products of combustion or superheated 55 steam may be used for this purpose. When superheated steam is used the sides of the retorts are perforated and the superheated steam mixes with the fuel in the retorts and with the gases distilled off. This also

greatly lessens the time of coking. When products of combustion are used for heating, which permits of a less expensive plant in that it eliminates high temperature superheaters, the retorts are made with solid walls 60 so that the gases for heating are separated from the products of distillation.

In order to prevent the breaking up of the products of distillation by bringing them into contact with higher temperatures 65 than those at which they were generated the heating of the retorts is accomplished by bringing in the hot gases near the bottom of the retorts and conducting off the products of distillation near the tops of the 70 retorts. The heating progresses from the bottoms upward.

In order to lessen the labor in the charging of the retorts, sealed covers are used 75 top and bottom. Each set of covers closing a plurality of retorts.

The accompanying drawings which form a part of this specification illustrate more fully my invention. Referring to the drawings in which like numerals designate like 80 parts in the various figures thereof. Figure 1 shows a plan in part section, of my apparatus. Figure 2 is an elevation in section taken on the line $\alpha\alpha$ of Figure one. Figure 3 is a longitudinal elevation in section taken on the line yy of Figure 1. Figure 4 shows a detail of the dog 25.

Fig. 5 is an elevation showing the hooks for supporting the sealing cover.

Referring to the drawing, the numeral 1 90 indicates a heating chamber which is provided with an insulated covering 19 in which are contained the retorts 2. These retorts are arranged vertically and placed side by side in the heating chamber. The 95 plan view Figure 1 shows two parallel rows of retorts in the one heating chamber. As many rows as are desirable may be located in any one heating chamber. The sides of the retorts 2 are made solid where products 100 of combustion are used for heating. Where superheated steam is used the sides are perforated with slots or the perforations 24. The retorts 2 are preferably made from cast iron and are separated from each other by a small gas space 17 approximately one inch in width. The retorts 2 in plan have a much greater length than they have breadth so that the heat is transmitted principally from 105 the side walls into the fuel contained. The 110

retorts in each row connect at the top into a common header 5 and at the bottom into a common header 10. The top header 5 is provided with a cover plate 7 which is sealed in the groove 8. The bottom header 10 is provided with a cover plate 13 and the seal 22. At the bottom of the retorts 2 and in the header 10 a swinging bottom 11 is hinged at 14. This bottom supports the fuel 10 in the retorts 2 and is held in the position shown by means of dogs or latches 25. Figure 4 shows a detail of the dog 25 and the bottom 11 when the lower end of the dog 25 is pushed to the right, the dog 25 passes through the slot 27 as the bottom drops. The latches 12 are provided on the ends of the headers 10, for supporting the sealed covers 22 as shown in Figure 5 in which 10^a represents a stud in the header 10 to which is pivoted the latch 12. This latch engages the stud 22^a in the cover 22. When the latch is pushed to one side, the cover 22 drops. The fuel could be supported directly on the cover plates 13. The swinging bottom 11 however, is a more desirable arrangement.

Between each row of retorts is located at the bottom of the heating chamber 1, a supply pipe 16, which supplies hot gas through the perforations 18 extending lengthwise of the pipe 16 for heating the retorts 2. At the top of the heating chamber and between each row of retorts the gas off-take pipe 15 is provided for removing the heating medium. This pipe is also provided with perforations 18 for admitting the heating medium. The perforations 18 are used to distribute the heating medium uniformly through the length of the heating chamber.

Outlet connection 6 communicating with headers 5 are provided for the removal of the products of distillation.

The operation of the apparatus is as follows:

The top cover plates 7 are removed, the swinging bottom 11 raised into the position shown on the drawings for supporting the fuel and the bottom cover plate 13 raised into position. The coal is then charged into the retorts 2, and the top cover plates 7 placed in position.

Where superheated steam is used as the heating medium the sides of the retorts 2, are perforated with the perforations 24. The superheated steam at a temperature under 1200 degrees F. is admitted under a pressure of a few pounds through the supply pipes 16. This steam rises around the retorts 2 and passes out through the pipes 15 and the outlet connection 6 together with the products of distillation from the fuel. This mixture of steam and products of distillation passes out to a common header or pipe line which is maintained under a slight vacuum by means of a gas exhauster. The exhauster draws the products through the ordinary gas

condensing and scrubbing equipment where the by-products of tar and ammonia are removed.

Where products of combustion are used for heating the retorts the products of distillation pass out to the exhauster through the outlets 6 while the products of exhaust used in heating the retorts pass out to a stack through the pipes 15.

After the fuel is coked, the covers are removed, the swinging fuel supports 11 dropped and the fuel discharged. The retorts are then refilled and the operation repeated.

From the foregoing description it will be seen that simple and efficient means are herein provided for the rapid devolatilization of fuel. While the elements shown and described are well adapted to serve the purpose for which they are intended, it is to be understood that the invention is not limited to the precise construction set forth but includes within its purview such changes as may be made within the scope of the appended claims.

What I claim is:

1. In apparatus of the type described, a heating chamber, a plurality of narrow retorts extending vertically through the said heating chamber, a gas space surrounding each retort, an upper header communicating with the upper ends of a plurality of the said retorts, a lower header communicating with the lower ends of the same said plurality of the said retorts, and a fuel support located within the said lower header and adapted to support the fuel in the retorts communicating therewith.

2. In apparatus of the type described, a heating chamber, a plurality of narrow retorts extending vertically through the said heating chamber, a gas space surrounding each retort, an upper header communicating with the upper ends of a plurality of the said retorts, a gas offtake pipe communicating with the said upper header, a lower header communicating with the lower ends of the same said plurality of retorts, a fuel support located within the said lower header and adapted to support the fuel in the retorts communicating therewith and covers for the said upper and lower headers.

3. In apparatus of the type described, a heating chamber, a plurality of narrow retorts extending vertically through the said heating chamber, an upper header communicating with the upper ends of a plurality of the said retorts, a gas offtake pipe communicating with the said upper header, a lower header communicating with the same said plurality of retorts, sealed covers for the top and bottom headers, means for the discharge of a heating medium on each side of the said retorts and near the bottom thereof, and means for taking off the said

heating medium on each side of the said retorts and near the top thereof.

4. In apparatus of the type described, a heating chamber, a plurality of rows of narrow vertical retorts extending lengthwise of the said heating chamber, an upper header communicating with a plurality of the upper ends of the said retorts in a row, a gas off-take pipe communicating with the 10 said upper header, a lower header communicating with the same said plurality of retorts in a row, and a fuel support located within the said lower header and adapted to support the fuel in the retorts communicating therewith.

5. In apparatus of the type described, a heating chamber, a plurality of rows of narrow vertical retorts extending lengthwise of the said heating chamber, an upper 20 header communicating with the upper ends of a plurality of the said retorts in a row, a gas offtake pipe communicating with the said upper header, a lower header communicating with the lower ends of the same said 25 plurality of retorts, a fuel support located within the said lower header, and sealed covers for the said top and bottom headers.

6. In apparatus of the type described, a heating chamber, a plurality of rows of narrow 30 vertical retorts extending lengthwise through the said heating chamber, an upper header communicating with the upper ends of a plurality of the said retorts in a row, a gas offtake connection communicating with the said upper header, a lower header communicating with the lower ends of the same said plurality of retorts in a row, a pipe for the discharge of a heating medium on each side of each row of the said 35 retorts and near the bottom thereof, an off-take pipe on each side of each row and near the top thereof, and sealed covers for the upper and lower headers.

7. In apparatus of the type described, a heating chamber, a plurality of rows of narrow vertical retorts extending through the said heating chamber, an upper header communicating with the upper ends of a plurality of the retorts in a row, perforation 45 through the side walls of the said retorts, a pipe for the display of superheated steam extending between each of the rows of said retorts, and between the end row and the side of the said heating chamber and near the bottom thereof, and a gas outlet connection 50 communicating with the said upper header.

8. In apparatus of the type described, a heating chamber, a plurality of rows of narrow vertical retorts extending through the said chamber, an upper header communicating with the upper ends of a plurality of the retorts in a row, perforation 60 through the side walls of the said retorts, a pipe for the discharge of superheated steam extending between each of the said rows of retorts and between the end row and the side of the said heating chamber and near the bottom thereof, a gas outlet connection communicating with the said upper header and a gas off-take 65 pipe extending between each of the said rows of retorts and between the end row and the side of the said heating chamber and near the top thereof.

9. In apparatus of the type described, a heating chamber, one or more rows of narrow retorts extending vertically through the said chamber, a gas pipe for the discharge of the heating medium extending along each side of each row of retorts and near the bottom thereof, and an off-take 70 pipe for the removal of the said heating medium extending along each side of each row of retorts and near the top thereof.

10. In apparatus of the type described, a heating chamber, a plurality of rows of vertical retorts extending through the said heating chamber, perforations in the side walls of the said retorts, an upper header communicating with the upper ends of a 80 plurality of the retorts in a row, a gas outlet connection communicating with the said upper header, a sealed cover for closing the said upper header, a lower header communicating with the lower ends of the above 85 said plurality of retorts, a swinging fuel support within the said lower header, a sealed cover for closing the bottom of the said lower header, a pipe for the discharge of superheated steam extending along each 90 side of each row of retorts and near the bottom thereof, and a pipe for the removal of the said superheated steam and other products extending along each side of each row of retorts and near the top thereof, substantially as described.

In testimony whereof I have signed my name to this specification in the presence of two subscribing witnesses.

CLAUDE M. GARLAND.
